United States Patent Office

Des. 206,191
Patented Nov. 8, 1966

206,191

EYESHADE OR SIMILAR ARTICLE

Paul A. Lawrence, 1660 Beaver, Des Moines, Iowa

Filed Oct. 13, 1965, Ser. No. 87,460

Term of patent 14 years

(Cl. D57—1)

FIGURE 1 is a front perspective view of an eyeshade or similar article showing my new design;

The broken line showing in FIG. 1 is for illustrative purposes only.

I claim:

The ornamental design for an eyeshade or similar article, substantially as shown and described.
